UNITED STATES PATENT OFFICE.

EUGÈNE RAFER AND EDMOND RAFER, OF SAINT-CHAMOND, FRANCE, AS-SIGNORS TO SOCIÉTÉ INDUSTRIELLE DES TRESSÉS & LACETS DE SAINT-CHAMOND, OF SAME PLACE.

BRAIDING-MACHINE.

SPECIFICATION forming part of Letters Patent No. 278,669, dated May 29, 1883.

Application filed January 30, 1883. (No model.) Patented in France April 28, 1877, No. 118,155; in Germany July 16, 1880, No. 12,319; in England May 26, 1882, No. 2,510; in Italy May 27, 1882, No. 14,264, and in Austria November 25, 1882.

To all whom it may concern:

Be it known that we, EUGÈNE RAFER and EDMOND RAFER, both citizens of the Republic of France, and residents of Saint-Chamond, France, have invented certain Improvements in Braiding-Machines for the Manufacture of Braid, Stay-Laces, &c., (for which we have obtained French Patent No. 118,155, April 28, 1877; German Patent No. 12,319, July 16, 1880; British Patent No. 2,510, May 26, 1880, and Italian Patent No. 14,264, May 27, 1882,) of which the following is a specification.

Our invention relates to a braiding-machine in which a series of rotating carriers are combined with traveling bobbin-holders traversed by said carriers and automatically transferred from one carrier to another; and the main object of our invention is to so construct a braiding-machine of this character that the bobbin-holders will be transferred from one carrier to another with the least possible shock, noise, or friction, and without liability of the threads breaking. This object we attain as more fully described hereinafter.

In the accompanying drawings, Figure 1 is a sectional plan view or diagram of sufficient of a braiding-machine to illustrate our invention, the carriers and the gear-wheels being omitted and the notched disks shown in dotted lines. Fig. 2 is a vertical section of one of the rotating carriers for the bobbin-holders, drawn to a smaller scale than Fig. 1. Fig. 3 is a sectional view of the double cam for the end carriers of the series; Fig. 4, a sectional plan view of the same; Fig. 5, a section of a modification; Fig. 6, a plan view of the same; Figs. 7 and 8, detached views of a part of Figs. 5 and 6. Fig. 2bis is an enlarged sectional plan view of two adjoining carriers, taken on the line 3 4, Fig. 2. Fig. 3bis is an enlarged detached view of one of the swinging gripper-rods for the bobbin-holders; Fig. 3ter, a plan of the same. Fig. 4bis is an enlarged detached view of one of the bobbin-holders with the bobbin removed, and Fig. 4ter is an enlarged plan view of two of the cams for operating the gripper-rods.

The operative parts of the machine are

mounted on a fixed circular base or plate, B, to which are secured as many stationary vertical spindles D and fixed cams C C and C' C' as there are rotary carriers H for the bobbin-holders, four being shown in the present instance. Each carrier H consists of a hollow spindle mounted and free to turn on the fixed spindle D, and having notched guiding-disks m m', and a pinion, N, Fig. 2, gearing into a similar pinion on the adjoining carrier, whereby motion is transmitted from one to the other, rotary motion being imparted to any one of the pinions, in the first instance, by suitable gearing from a driving-shaft, N', as indicated by dotted lines, for instance, in Fig. 1.

To bearings in the disk m and pinion N of each carrier are adapted vertical gripper-bars A, Figs. 3bis and 3ter, five being shown on each of the end or return carriers H, Fig. 2, and four on each of the intermediate carriers. Each gripper-bar A carries a pair of gripping-claws, G, and has at its lower end a cranked portion, M, adapted to the groove in the fixed cam C, (or C'). Each disk m m' has as many semi-cylindrical notches o, Fig. 2bis, in its edge as there are gripper-bars A, and immediately adjacent thereto for the purpose of receiving the stems f of the bobbin-carriers F, Figs. 2 and 4bis, which are temporarily held in the said notches by the claws G of the corresponding gripper-bar A. The carriers are so timed in their movements that the notches in the disks of adjoining carriers always come opposite each other, Fig. 1. Each holder F carries a bobbin or spool, F', of yarn or thread, and there are as many bobbin-holders as there are to be strands of thread in the braid to be made, nine of these holders being shown in Fig. 1. Each of the intermediate cams, C C', has only a single cam-groove to control (through the cranks M) the opening and closing of the four gripper-claws in each revolution, while the end or return carriers are somewhat larger, and each has five gripper-bars and five notches o in each disk m, (m'), with a cam, C, having double grooves E E' and switches, Figs. 3, 4, and 4ter, to keep each of the gripper-claws of that carrier closed during one revolution and

open during the next. For this purpose each cam C is provided with two switches, P P', pivoted at p and p', respectively, on the line of the dividing-rib between the two grooves 5 E and E', Fig. 4ter.

Supposing the carrier to be traveling in the direction of the arrow, Fig. 4ter, and M to represent the crank of one of the five gripper-bars, the switches being in the position shown, 10 the crank M will be guided into the inner groove, E', by the switch P, and as it passes on will throw the said switch to the position indicated by dotted lines, and the four succeeding crank-pins will so act on the switch 15 P that by the time this crank M gets around the groove E' to the position shown the switch P will be in the position indicated by dotted lines, so that the said crank-pin will on this succeeding revolution be transferred to and 20 travel in the outer groove, E. When the crank of a gripper-bar A is traveling in the outer groove its claws G are in the closed position to hold the stem f of a bobbin-holder, F, in the notches o of the carrier-disks m m', 25 while when the crank M is traveling in the inner groove, E', the claws G are open to release the bobbin-holder. The switches P P' are of such a length that the crank-pin of one gripper-bar comes into contact with one end 30 of a switch just as the preceding crank-pin is about to leave the other end, and thus rebounding of either switch into the wrong position is prevented.

Supposing the parts to be in their several 35 positions indicated in Fig. 1 and the several carriers H rotating in the directions of their arrows, we will explain the path taken by one of the bobbin-holders F, with its bobbin and thread to form the braid, with the other threads 40 simultaneously traversed in a similar manner. Beginning with a holder F at the position 5, the said holder being held by the gripper-claws G to the rotating carrier No. 1, the carrier 1 will traverse the holder until it comes into line 45 with notches o in the disks of carrier No. 2, when the cam of carrier No. 1 will have so operated the crank of that gripper-bar that its claws will release the holder F, while at the same moment the gripper-rod A on carrier No. 50 2, immediately opposite, will have been closed on the said holder to clasp it to the rotating carrier No. 2, which will traverse it in the direction of the arrow. (See position 6.) When this holder comes into notches in the disks m 55 m' of carrier No. 3 the gripper-claws of No. 2 will open and release the holder, while at the same moment gripper-jaws on No. 3 will close and clasp the holder to No. 3 carrier and traverse it in the direction of its arrow, as indicated at positions 7 and 8, all the way round 60 until it comes to the position 9, when the crank of the gripper-rod A will be transferred from the outer cam-groove, E, to the inner groove, E', Fig. 4ter, so as to open the claws and release the holder F at 9, which is simultaneously 65 grasped by gripping-claws on carrier No. 2. It is then carried partially around to No. 1 and

transferred to the latter, and partly around No. 1 (see position 10) to No. 4, (see position 11,) and, owing to the double cam C, carried 70 round No. 4 carrier back to No. 1, thence to No. 2 and No. 3, as before, all the other eight holders F being at the same time traversed in and out in a similar manner. By these 75 means the bobbin-holders are traversed and transferred from one carrier to another without shock or noise, and without breakage of threads.

It will be observed, on reference to Fig. 1, that in each of the intermediate carriers (Nos. 80 1 and 2) two diametrically-opposite grippers have their claws facing in one direction with reference to the rotation of the carrier, while the other two have their claws facing in the reverse direction, and also the two diametri- 85 cally-opposite grippers of one pair have their cranks M about at right angles to their claws, while the two grippers of the other pair have their cranks nearly in line with the claws. The reason for these differences in the "set" 90 of the grippers is that one pair transfers the bobbin-holders in one direction while the other pair transfers them in the opposite direction. Thus the two grippers of No. 1, which have their cranks at right angles to their claws, 95 transfer the bobbin-holders from the carrier No. 2 to the carrier No. 4, while the other pair are for transferring the holders from No. 4 to No. 2 again.

Instead of using pivoted switches P P' on the double cams C C, we may make use of the stationary switch-cam illustrated in Figs. 5 and 6. It will be seen, on reference to these figures, that the dividing-rib between the grooves E E' is cut away at z z, and at this point is inserted a stud, x, projecting slightly above the bottom of the groove, and having two curved channels, r r', cut in its surface crossing each other, and each opening on one end into the inner groove, E', and at the other end into the outer groove, E. To these grooves is adapted a traveling shoe, s, Figs. 5, 6, 7, and 8, having on its under side a rib adapted to enter the cross-channels r r' to guide the shoe, in its rotary motion, from the inner groove to the outer groove, and from the outer to the inner one, as will be readily understood. This shoe has a recess in its upper face for the reception of the crank M of the gripper-bar, which is thus operated as before described.

We claim as our invention—

1. The combination of the rotary carriers having notched disks for the bobbin-holders, with a series of cranked gripper-rods, A, mounted in said carriers, and stationary grooved cams 125 adapted to operate said gripper-rods, substantially as set forth.

2. The combination of the bobbin-holders F, having stems f, and rotary carriers having notched disks for said holders, with a series of 130 cranked gripper-rods, A, mounted in said carriers, and stationary grooved cams to which the cranked ends of the rods are adapted, substantially as described.

3. The combination of a series of rotary carriers for the bobbin-holders, with cranked gripper-rods mounted in said carriers, and grooved cams to which the cranked ends of the rods are adapted, the end cams of the series having double grooves and switches, substantially as set forth.

In testimony whereof we have signed our

names to this specification in the presence of two subscribing witnesses.
